The ornamental design for a case for cards and card packs, as shown and described.

Dec. 28, 2004 (JP) 2004-040376

DESCRIPTION(51) **LOC (8) Cl.** **03-01**

This article relates to a case for cards and card packs for receiving both cards and card packs containing a plurality of cards.

(52) **U.S. Cl.** **D3/299; D21/392**

FIG. 1 is a front side elevation view.

(58) **Field of Classification Search** D3/205,

FIG. 2 is a rear side elevation view.

D3/230, 273, 299, 319, 905; D19/26; D21/376,
D21/392-393, 396; 273/148 A, 149 P, 149 R,
273/157 A; 206/39.4, 315.1

FIG. 3 is a right side elevation view.

See application file for complete search history.

FIG. 4 is a left side elevation view.

FOREIGN PATENT DOCUMENTS

FIG. 7 is a front side elevation view for reference.

JP	2001-080239	3/2001
JP	2001-270584	10/2001

FIG. 8 is a cross-sectional view taken along line 8—8 in FIG. 7.

JP

FIG. 9 is a cross-sectional view taken along line 9—9 in FIG. 7.

JP

FIG. 10 is an enlarged cross-sectional view taken along line 10—10 in FIG. 7.

JP

FIG. 11 is an enlarged cross-sectional view taken along line 11—11 in FIG. 7.

JP

FIG. 12 is a perspective view for reference as viewed from the front.

JP

FIG. 13 is a perspective view of a half-opened case for reference as viewed from the front.

JP

FIG. 14 is a front side elevation view thereof but with the transparent covers removed.

JP

FIG. 15 is a right side elevation view thereof but with the transparent covers removed.

JP

FIG. 16 is a left side elevation view of a case without a cover.

JP

FIG. 17 is a top plan view of a case without a cover.

FIG. 18 is a bottom plan view of a case without a cover.
FIG. 19 is a perspective view of a case without a cover for reference as viewed from the front.
FIG. 20 is a perspective view of a half-opened case for reference as viewed from the front.
FIG. 21 is a front side elevation view of the transparent cover portion of the design.
FIG. 22 is a rear side elevation view of the transparent cover portion of the design.
FIG. 23 is a right side elevation view of a cover.
FIG. 24 is a top plan view of a cover.

FIG. 25 is a perspective view of a cover for reference as viewed from the front.
FIG. 26 is a perspective view for reference in which a case is folded; and,
FIG. 27 is a perspective view exploded view for reference. The broken line showing in FIGS. 1, 2, 5-7, 12-14, 16-20, 26, and 27 is for illustrative purposes only and forms no part of the claimed design.
